UNITED STATES PATENT OFFICE.

JOSEPH B. MORGAN, OF JANEVILLE, WISCONSIN.

WHIPLASH.

1,413,485.

Specification of Letters Patent. Patented Apr. 18, 1922.

Application filed July 7, 1921. Serial No. 482,075.

To all whom it may concern:

Be it known that I, JOSEPH B. MORGAN, a citizen of the United States, residing at Janesville, in the county of Rock and State 5 of Wisconsin, have invented certain new and useful Improvements in Whiplashes; and I do declare the following to be a full, clear, and exact description of the invention, such as will enable others skilled in the art to 10 which it appertains to make and use the same.

This invention relates to an improved lash which is especially designed for attachment to whips of the type used by teamsters, 15 which type of whips are usually provided with extremely long lashes for enabling the whip to extend over a considerable distance so that it can be used on the foremost horses which are some distance ahead of the 20 driver's seat as in cases where the horses are attached to binding machines and the like.

The ordinary lash employed on whips of this type is necessarily extremely long and when used by drivers on machines of the 25 type above mentioned, it often becomes entangled with some part of the machine during the use thereof. This, of course, is undesirable and in order to overcome this objectionable feature, I contemplate substituting for the types of lashes now employed, 30 one of relatively short length which will stretch when thrown out for use and accomplish the same result that the extremely long lash now used does.

One of the principal aims of the invention 35 is to provide a lash of this type which is such in construction that it can be attached to the usual existing loop on the end of the flexible portion of an ordinary teamster's 40 whip, the lash itself being equipped at its outer end with a similar loop to permit an ordinary snap to be connected therewith.

In the accompanying drawings forming 45 a part of this specification and in which like numerals are employed to designate like parts throughout the same:

Figure 1 is an elevational view of a conventional type of teamster's whip equipped with a lash constructed in accordance with 50 this invention.

Figure 2 is a view of the lash detached showing the same extended for use.

Figure 3 is a slightly enlarged view show-

ing a portion of the covering broken away and shown in section to disclose the construction and arrangement more clearly.

Referring to the drawings by reference characters, A designates generally an ordinary type of teamster's whip such as is used by drivers of binding machines, or 60 other vehicles drawn by a large number of horses. The flexible forward portion of this whip, as is usual, is equipped at its free end with an attaching loop B to which the ordinary type of lash is detachably connected. 65 Instead of employing the ordinary lash, I substitute my improved elastic lash therefor, the same being designated generally by the numeral 1 and having a loop 2 as its inner end for detachable connection with the loop 70 B of the whip A, the two loops being connected together in the manner shown. At its outer end, my improved lash is also provided with another loop 3 which is designed to have detachable connection with the loop 75 C on the inner end of a conventional form of snap D. While the lash may be constructed otherwise, it preferably comprises a length of elastic material 4 covered by a stretchable wrapping or cover 5. Here it 80 may be stated that this covering 5 will preferably be formed from cotton and so woven that it will be permitted to stretch a considerable distance, at least enough to permit a relatively short lash of this construction 85 to accomplish the result of a comparatively long lash of the ordinary construction. The lash necessarily embodies means to carry it forward to the extreme point where it can be used on the foremost horses and this 90 means preferably consists of a plurality of small lead weights 6 which in the showing are provided with holes through which the elastic element 4 is passed. With this construction and arrangement, it will be seen 95

that as the whip is thrown out to act on the foremost horses or any other horses, the weights will serve to stretch the lash so that it will assume an extended position somewhat like that indicated in Fig. 2. Hence, 100 it will be possible for this relatively short lash to extend over a considerable distance.

Since probably the best results may be obtained with the construction and arrangement herein shown and described, a more 105 lengthy description is deemed unnecessary.

However, slight minor changes coming within the scope of the subjoined claims may be resorted to.

I claim:

- 5 1. An elastic lash for whips including means for stretching the same when thrown out or extended for use.
2. A lash for whips comprising a length

of elastic material, a stretchable covering therefor, and weights for extending said material and covering when cast forwardly by the driver.

In testimony whereof I have hereunto set my hand.

JOSEPH B. MORGAN.
